(57) **CLAIM**

The ornamental design for a light fixture, as shown and described.

DESCRIPTION

FIG. 1 is a perspective view showing the front, bottom and right side of our new design for a light fixture in a ceiling mount orientation;

FIG. 2 is a bottom plan view of the fixture shown in FIG. 1; FIG. 3 is a front elevation of the fixture shown in FIG. 1; FIG. 4 is a side elevation of the fixture shown in FIG. 1, of which the opposite side is a mirror image;

FIG. 5 is a top plan view of the fixture shown in FIG. 1, with phantom lines indicating a wall thickness which forms no part of the claimed design; and,

FIG. 6 is a perspective view of the fixture shown in FIG. 1 in a wall mount orientation showing the bottom, front and right side, which in FIG. 1 would be the rear, bottom and right side, respectively.
